FIG. 6

HERMANN RUETSCHI,
BY
Fred C. Graentzel,
ATTORNEY

INVENTOR:

UNITED STATES PATENT OFFICE.

HERMANN RUETSCHI, OF NEWARK, NEW JERSEY.

HEAT-DETECTOR.

SPECIFICATION forming part of Letters Patent No. 591,143, dated October 5, 1897.

Application filed March 25, 1897. Serial No. 629,270. (No model.)

To all whom it may concern:

Be it known that I, HERMANN RUETSCHI, a citizen of the United States, and a resident of Newark, in the county of Essex and State 5 of New Jersey, have invented a certain new and useful Heat-Detector, of which the following is a specification.

My invention has reference to improvements in that class of circuit-closers in which 10 contact is made or broken by excessive heat, and a consequent rise in temperature, by the sounding of an alarm arranged in the circuit in which the circuit-closing device is placed.

The main object of my invention, therefore, 15 is to provide a device of this nature to be used as a temperature-indicator, serving, for instance, when there is a rise in the temperature caused by a fire in the building as an automatic indicator to warn the person or 20 persons in the building by the sounding of an electric alarm-signal.

The device is also designed for use in greenhouses, incubators, &c., or in factories, where 25 an even temperature is required, the device serving as an automatic indicator to give notice when the temperature is above that desired.

A further object of the invention is to provide in connection with the apparatus a simple means for rendering the device adjustable 30 for the purposes for which it is intended.

The invention consists in the improved circuit-closer hereinafter set forth, and also in the novel arrangements and combinations of 35 the several parts more fully described in the accompanying specification and finally embodied in the clauses of the claim.

The invention is illustrated in the accompanying drawings, in which— 40 Figure 1 is a view of the device inclosed in an ornamental casing, illustrated in a circuit containing a battery and an electric alarm-bell. Fig. 2 is a face view of the circuit-closer, the said ornamental casing being removed to more clearly show the arrangement 45 of the several parts of the device. Fig. 3 is a side view of the device, and Fig. 4 is a longitudinal section taken on line 4 4 in said Fig. 2. Fig. 5 is an end view of the device; 50 and Fig. 6 is a cross-section of the same, taken on line 6 6 in Fig. 4. Fig. 7 is a perspective

view of a spring employed in connection with the device provided with a contact portion which causes the circuit connected with the device to be closed when there is an excessive 55 rise of temperature.

Similar letters of reference are employed in all of the above-described views to indicate like parts.

In said drawings, A indicates the contact 60 or circuit-closer, provided with a suitably-ornamented cover b, of metal or any other suitable material, provided with perforations or holes, as b', to permit the heat to more quickly come in contact with the operative 65 parts of the circuit-closing device within said casing. The said circuit-closing device proper consists, essentially, in the arrangement of two parallel bars a and a', of wood, slate, or any other desirable material, which may be 70 provided with suitable openings, as a². Said bars a and a' are placed side by side in such a manner as to form a longitudinal space a³ between them, which is formed by the arrangement of metallic plates or blocks c and 75 c', secured between said bars at or near the ends thereof by means of suitable screws c³, as clearly shown in Figs. 4 and 5. Said bars a and a' are secured together, with the said metallic plates or blocks c and c' between 80 them, by means of the screws a⁴, and a⁵ are the screws for securely attaching the device to the ceiling or wall of a room or in any other place where the device is to be put up.

Each plate or block c and c' is provided with 85 a suitable hole in which I arrange the ends d' and d² of a very fine wire d, of any suitable metal, having great strength and capable of ready expansion when exposed to an ordinary rise in the temperature, which wire 90 when suitably stretched is secured in said holes in the said plates or blocks c and c' by means of suitable set-screws c². To prevent the points of said screws from cutting or breaking the ends of the said fine wire d 95 when the screws are firmly screwed down, I may arrange in said holes in the plates or blocks c and c' in position between the fine wire d and the ends of the screws small pieces or plates, as c⁴, which act as protector-plates 100 against the action of the screw-points against the fine wire.

As will be more especially seen from Fig. 6, the bar *a* of the device A is provided at its central point with an electric contact or post *e* and screw *e'*, adapted to receive the other 5 end of the circuit-wire *g*, in which I have arranged a battery *g'* and an electric alarm-bell *g''*, as clearly illustrated in Fig. 1.

In an opening *a'* in the bar *a* I have arranged a contact-screw *h*, which is screwed 10 into the post *e*, as shown in Fig. 6, and in an opening *a''* in the bar *a'* is a screw *h'*, which screws into the back of the post *e'*, said screws *h* and *h'* respectively securing said posts *e* and *e'* in their operative positions on the bars 15 *a* and *a'*, substantially as illustrated. Connected with the said screw *h* by means of a loop or eye *i'* is a suitable contact-spring *i*, preferably made of phosphor-bronze, provided with a coil *i''* and an arm *i'''*, said arm 20 having a flattened end *i''*, which is preferably provided with a platinum contact *i'''*. Said flattened end *i''* is bent at a suitable angle, as at *i'''*, and has a hole or perforation *i''''*, through which the wire *d* passes, as clearly 25 illustrated in Fig. 4.

Extending from one side of the contact-post *e'* to a point directly above the flattened end *i''* of said spring *i* is a bar *e''*, and in a screw-threaded hole in said bar is an adjustable screw *e'''*, which acts as a contact, and preferably has a platinum contact-point on 30 its free end. When said portion *i''* of the spring *i* is in contact with the end of said screw *e'''*, then a complete circuit will be established through the several parts of the 35 device A and the circuit *g*, whereby an alarm will be sounded by the electric bell *g''*, as will be clearly understood.

Under normal conditions the wire *d* is contracted and very taut, and the wire passing 40 through the perforated end *i''''* of the spring *i* said end of the spring will be out of electrical contact with the screw *e'''* and the main circuit will of course be broken; but as soon as 45 there is an increase of temperature the wire *d* will expand, which allows the coils *i''* of the spring *i* to act and bring the contact portion *i''* of the end *i''* of the spring *i* into operative 50 electrical contact with the screw *e'''*, with the result hereinabove mentioned.

The operation of the parts is clear and very simple, and a circuit-closer is the result which is very useful for many purposes.

Of course it will be understood that the device can be made to work at different temperatures by means of the regulating-screw *e''*, which can be brought farther away or closer to the contacting surface of the spring *i* by turning the screw in said bar *e''*, as will be clearly understood.

Having thus described my invention, what I claim is—

1. The herein-described circuit-closer, comprising, in combination, with an open frame, a fine metallic wire stretched in said frame, a pair of electrical contacts in said frame, and a spring in said frame, said spring having

a perforated contact end portion, through which said wire passes, to normally force said spring out of contact with one of said electrical contacts on said frame, substantially as and for the purposes set forth. 70

2. The herein-described circuit-closer, comprising, in combination, with an open frame, a fine metallic wire stretched in said frame, a contact-post *e*, a screw *h* connected with said post, a spring in said frame, said spring having a perforated contact end portion, through which said wire passes, and a contact-post *e'* and a contact-screw, with which said spring 75 is adapted to make contact, substantially as and for the purposes set forth.

3. The herein-described circuit-closer, comprising in combination, with a pair of bars *a* and *a'*, metallic blocks *c* and *c'* between said bars and a fine wire connected with said blocks, a pair of electrical contacts, one on each bar *a* and *a'*, and a spring connected with one of said bars, said spring having a perforated contact end portion, through which said wire passes, to normally force said spring 80 out of contact with one of said electrical contacts, substantially as and for the purposes set forth.

4. The herein-described circuit-closer, comprising, in combination, with a pair of bars *a* and *a'*, metallic blocks *c* and *c'* between said bars and a fine wire connected with said blocks, a contact-post *e* on said bar *a*, a screw *h* connected therewith, a spring connected 90 with said bar *a'*, having a perforated contact end portion, through which said wire passes, a contact-post *e'* on said bar *a'* and a contact-screw *e'''*, with which said spring is adapted to make contact, substantially as and for the 95 purposes set forth.

5. The herein-described circuit-closer, consisting, essentially, of a pair of bars *a* and *a'*, metallic blocks *c* and *c'* between said bars, a fine wire connected with said blocks, and a spring *i* between said bars, said spring having a perforated contact end portion, through which said wire passes, and a contact on one of said bars, with which said spring is adapted to make contact, substantially as and for the 105 purposes set forth.

6. The herein-described circuit-closer, consisting, essentially, of a pair of bars *a* and *a'*, metallic blocks *c* and *c'* between said bars, a fine wire connected with said blocks, a contact-post *e* on said bar *a*, a contact-screw *h* connected with said post *e*, a contact-post *e'* on said bar *a'*, a bar *e''* connected therewith, a contact-screw *e'''* on said bar *e''*, and a contact-spring connected with said screw *h*, said spring 110 having a perforated contact end portion, through which said wire passes, substantially as and for the purposes set forth.

7. The herein-described circuit-closer, consisting, essentially, of a pair of bars *a* and *a'*, metallic blocks *c* and *c'* between said bars, a fine wire connected with said blocks, a contact-post *e* on said bar *a*, a contact-screw *h* connected with said post *e*, a contact-post *e'* on said

bar a' , a bar e^4 connected therewith, a contact-screw e^5 on said bar e^4 , and a contact-spring connected with said screw h , said spring having a coiled portion i^2 , an arm i^3 , a flattened end contact portion i^4 , and a perforated bent part i^5 , through which said wire passes, substantially as and for the purposes set forth.

Signed at Newark, in the county of Essex and State of New Jersey, this 23d day of March, A. D. 1897.

HERMANN RUETSCHI.
